DESIGN FOR A CASING FOR PENCIL SHARPENER

Robert Campbell, Flushing, N. Y.

Application April 8, 1935, Serial No. 56,268

Term of patent 3½ years

To all whom it may concern:

Be it known that I, Robert Campbell, a citizen of the United States, residing at Flushing, county of Queens, State of New York, have invented a new, original, and ornamental Design for a Casing for Pencil Sharpener, of which the following is a specification, reference being had to the accompanying drawing, forming a part thereof, in which

Fig. 1 is a perspective view of a casing for pencil sharpener showing my design.

Fig. 2 is a side elevational view of a casing for pencil sharpener, showing my design.

I claim:

The ornamental design for a casing for pencil sharpener as shown.

In witness whereof I affix my signature.

ROBERT CAMPBELL.
